J. E. MILLER.
TROUSERS PRESSING DEVICE.
APPLICATION FILED DEC. 5, 1911.

UNITED STATES PATENT OFFICE.

JAMES E. MILLER, OF BRADDOCK, PENNSYLVANIA, ASSIGNOR OF ONE-HALF TO JOHN J. SIXSMITH, OF HOMESTEAD, PENNSYLVANIA.

TROUSERS-PRESSING DEVICE.

1,038,778.

Specification of Letters Patent. Patented Sept. 17, 1912.

Application filed December 5, 1911. Serial No. 664,053.

To all whom it may concern:

Be it known that I, JAMES E. MILLER, a citizen of the United States, residing at 670 First street, Braddock, in the county of Allegheny and State of Pennsylvania, have invented certain new and useful Improvements in Trouser-Pressing Devices, of which the following is a specification.

The present invention relates to an improved trousers pressing device, and is designed to perfect devices of this character in several particulars.

Prominent among the advantages and meritorious features of the improved article are its simplicity of construction; durability and strength; lightness of construction; facility of manipulation; and above all its efficiency in operation, as the device not only creases the trousers, but performs the additional function of creasing the legs at front and rear, thus securing a neat and attractive appearance to the wearer of the trousers thus treated.

The invention consists in certain, novel details of construction and combinations and arrangements of parts as hereinafter set forth and more particularly pointed out in the claims.

In the accompanying drawings I have illustrated one example of the physical embodiment of my invention constructed according to the best mode I, have so far devised for the practical application of the principles.

Figure 1 is a side elevation of the device, in position to be hung up or suspended, when not in use. Fig. 2 is a sectional view on line A—A Fig. 1, illustrating a pair of trousers-creasing boards, and the mode of securing the pressing members in locked position. Fig. 3 illustrates two forms of trousers-creasing or filler boards, one form having a cut out on curved lines at one end, and the other form having a solid end, as indicated in dotted lines. Fig. 4 illustrates the mode of operation of the device, showing one leg in position. Fig. 5 is a section at B—B Fig. 4, showing the trousers clasped between the folding boards and in process of pressing. Fig. 6 is a fragmentary detail view showing the means of preventing warping or buckling of the boards by providing a strengthened hinge strap.

In the preferred embodiment of my invention I utilize the base board 1, and the

duplicate folding boards 2 and 3, which are usually made of thin material, such as wood.

The boards 1, 2, and 3 are connected together by means of the strap hinges, which as clearly shown in Fig. 2, extend entirely around the device when in folded and operative position, and in this manner strengthen the entire device and provide a compact and rigid construction.

In Fig. 6 it will be evident that the rib 4 of the strap 5, which forms part of the intermediate hinges 6, 6, will materially and substantially strengthen the device between the locking hinges.

Near each end of the device is located a locking hinge, each of which comprises a strap similar to strap 4 of the intermediate hinges 6, but the leaves 7, 7' are of a different construction than those of the intermediate hinge.

The leaves or straps 7 and 7' are jointed at 8 to the hinge strap 5 at the underside of the base board. At its inner free end the hinge strap or leaf 7 has pivoted thereto, by means of a pin 9, the lever 10, and this lever has loosely pivoted therein a locking ring 11, which is adapted to hook over the curled or hooked end 12 of the complementary strap 7', as clearly seen in Figs. 1 and 2.

Special attention is called to the fact that the straps 7 extend over and overlap the adjoining edge of the opposite folding board 3; that the under side of the adjoining edges of the boards 2 and 3 are beveled as at 13, and that a groove 14 extends the entire length of the base board, at its inner side, complementary to the groove formed by the beveled edges 13 of the folding boards.

A spring pressed wooden strip 15 is provided at one end of the base board and formed with a beveled inner face 16 to bear against the trousers legs, as seen in Fig. 5, and bring the outer face of the strip flush with the surface of the folding boards 2 and 3, to insure a neat appearance.

17 denotes a loop or suspending hook by means of which the device may be hung up in a clothes closet.

In actual use of the device I find it desirable to employ one and if necessary, two pressers boards as 18, made of pasteboard, or other light material of this character. One of the boards is inserted between the legs, and for this purpose is cut away, as at 19 to accommodate the fullness in the seat of 110

the trousers. The other board may be located under the folding boards, as seen in Fig. 5.

In operation, the device is laid upon a table with the base board 1 resting flat thereupon, and the spring clasp 15 is drawn back, as in Fig. 4. One leg is now placed upon the base board and smoothed out to eliminate the wrinkles. One of the boards 18 is now placed upon the smooth leg, and preferably a board with the cut out 19 is used, as shown in Fig. 4. The second leg is now laid over and smoothed out upon the paste board and the leg bottoms are clasped between the end 15 of the base board and the spring clasp 15. In Fig. 5 it will be seen that the paste-boards and the folding boards are not so long as the base board and this construction provides for the increased thickness of the leg bottoms 20 so that they may be held firmly between the clasp and base board, and Figs. 1 and 4 show the opposite ends of the folding boards cut away to allow for the increased fullness at the seat of the trousers. After the second 25 leg has been positioned the second paste-board is laid upon the trousers, and the boards 2 and 3 folded in toward each other, to the position shown in Fig. 2, where the rings 11 have been hooked over the curled end 12 of the strap 7'. The hinges are now 30 ready to be locked, and the levers 10 are swung over to the left in Fig. 2 to the position in Fig. 1. This movement draws the two folding board sections together, and the 35 overlapping hinge strap 7 presses down on the edge of the section 3 to securely and firmly lock the parts in a flat position pressing upon the inclosed trousers.

An inspection of Fig. 2 will illustrate the squeezing action of the folding boards upon the legs, which action, and the continued

pressure, forms a neat and serviceable crease at the front and back of the trousers legs.

Having thus fully described my invention, what I claim as new and desire to secure by 45 Letters Patent is:—

1. The combination with a base board and complementary folding boards hinged thereto, of a lever pivoted on one hinge strap on a folding board and carrying a ring, and 50 the hinge strap on the opposing folding board having a hooked end to receive said ring, whereby the folding boards may be folded down upon and held to the base board. 55

2. The combination with a base board and complementary folding boards and hinges connecting the parts, the hinge straps on one folding board adapted to overlap the adjoining edge of the opposite board, and having a lever pivoted thereon, a hooked hinge strap on the opposite board and a ring or loop carried by said lever to engage said hooked strap. 60

3. The combination with a base board and 65 complementary folding boards, the edges of the folding boards being beveled as described and the base board formed with a groove as described, hinges connecting the base board with the folding boards, the hinge straps on one folding board adapted to overlap the adjoining edge of the opposite board and having a lever pivoted thereon, a hooked hinged strap on the opposite board, and a ring carried by said lever adapted to 70 engage said hooked strap. 75

In testimony whereof I affix my signature in presence of two witnesses.

JAMES E. MILLER.
